CLAIM

(57) We claim the ornamental design for a display screen or portion thereof with icon, as shown and described.

DESCRIPTION

The FIGURE is a Front View of a display screen or portion thereof with icon showing our new design.

The broken line in the drawing illustrates the display screen in which the claimed design is embodied. Alternatively, the broken line illustrates the portion of the display screen in which the claimed design is embodied. The broken line showing of the display screen or portion thereof illustrates the environment of the claimed design and forms no part thereof.
